US0D1012162S

(12) **United States Design Patent** (10) **Patent No.:** **US D1,012,162 S**
(45) **Date of Patent:** **** Jan. 23, 2024**

(54) **SAFETY GLASSES**

(71) Applicant: **Milwaukee Electric Tool Corporation**,
Brookfield, WI (US)

(72) Inventor: **Casey Bonath**, Milwaukee, WI (US)

(73) Assignee: **Milwaukee Electric Tool Corporation**,
Brookfield, WI (US)

(**) Term: **15 Years**

(21) Appl. No.: **29/774,013**

(22) Filed: **Mar. 12, 2021**

Related U.S. Application Data

(62) Division of application No. 29/692,250, filed on May 23, 2019, now Pat. No. Des. 916,950.

(57) **CLAIM**

I claim the ornamental design for safety glasses, as shown and described.

DESCRIPTION

FIG. 1 is a front, top perspective view of safety glasses according to the present design;

FIG. 2 is a front, bottom perspective view thereof;

FIG. 3 is a rear, top perspective view thereof;

FIG. 4 is a rear, bottom perspective view thereof;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

The broken lines in the drawings illustrate portions of the article and form no part of the claimed design.

1 Claim, 8 Drawing Sheets
